UNITED STATES PATENT OFFICE.

NOE LARIVIERE, OF BALTIC, CONNECTICUT.

SHUTTLE-BINDER FOR LOOMS.

1,097,761.

Specification of Letters Patent.

Patented May 26, 1914.

Application filed June 13, 1913. Serial No. 773,432.

To all whom it may concern:

Be it known that I, NOE LARIVIERE, a citizen of the United States, residing at Baltic, in the county of New London and State of Connecticut, have invented a certain new and useful Improvement in Shuttle-Binders for Looms, of which the following is a specification.

This invention relates to the mechanism commonly provided in looms of the reciprocating batten type for checking and clamping the filling shuttle as it is thrown from end to end of said batten by the picker stick, and my present purpose is to provide novel and effective clamping mechanism by means of which the power required for throwing the shuttle will be materially lessened. With this desirable end in view I have provided the clamping device illustrated in the annexed drawings, in which—

Figure 1 is an end elevation of a loom batten and those parts connected therewith which relate particularly to my present improvement. Fig. 2 is a front side view of the same parts, and Fig. 3 is a relatively enlarged, plan view of one of the shuttle boxes, showing also the special form of finger provided by me for co-operating with said box to clamp the shuttle in its inactive position.

Referring to these drawings, the numeral 10 indicates the batten, or so called "lathe," of a loom, said batten being attached to, and carried by, the upper (free) end portions of so called swords 11 that are suitably hinged at their lower ends. The said batten is connected, by means of an arm 12, with a crank 14 carried by a shaft 15 which latter is journaled in the loom frame and is driven in the usual, or in any other suitable, manner; each revolution of said shaft causing the batten to swing forward and backward a prescribed distance in order to, first, permit the shuttle to be thrown along the batten between the separated warp threads and then to lay up the filling thread.

The numerals 16 indicate as a whole, shuttle boxes located at the opposite ends of the batten and adapted to receive the shuttle as it is forcibly thrown along said batten by the picker sticks. The mechanism most commonly provided by this type of looms for receiving and checking the shuttle consists of a box having one rigid side wall and an opposing spring controlled yielding side wall: the shuttle being thrown with such force that it crowds its way in between the

two described walls until it is stopped by the friction resulting from the sliding impact of the shuttle with side walls of the shuttle box.

In my present, improved, form of shuttle binder I provide a shuttle box, at each end of the batten, consisting of a rigid side 16^a and an opposed yielding, side 16^b which latter, as here shown, is hinged at 17. This yielding side 16^b is controlled as to its position by a finger 18 that is secured to a suitable rock-shaft 19 that is journaled in bearings 20 secured to the batten 10 and, by preference, I utilize for such shaft the so-called "protection rod" which is usually embodied in this type of looms. Secured to said shaft 19 is an arm 21 and hinged to the sword 11 is a similar arm 22 whose free end is connected, by means of a rod 23 with an angle arm or plate 24 that is adjustably pivoted to the crank arm 12 already mentioned. The free end of arm 21 has hinged thereon a rod 25 which extends downwardly, through the arm 22, and said rod has mounted on its lower end portion a spring 26, one of whose ends abuts the lower edge of said arm 22 and whose other end abuts a nut or collar 27 secured to the said rod, as is best seen in Fig. 1 of the drawings.

The arrangement of the described parts is such that each revolution of the crank-shaft 15 will operate to force the free end of arm 22 downward positively a given distance and, said arm 22 (through the medium of the rod 25, spring 26 and arm 21) will rock the shaft 19 and thus move the finger 18 inward, that is to say toward the shuttle box, a distance sufficient to move the hinged side 16^b of the shuttle box slightly into the path of the shuttle as the latter is thrown into said shuttle box. Meanwhile the spring 26 permits the finger 18 and the hinged side 16^b to yield slightly as the shuttle enters the box. Just at the instant when the picker stick is about to strike the shuttle to throw the latter out of the box and to the other end of the batten, the crank arm 12 and rod 23 raise the free end of arm 22, and the finger 18 is moved outwardly sufficiently to free the hinged side 16^b of the shuttle box and thus permit the shuttle to leave the box without the frictional hindrance common to the spring-controlled boxes now in almost universal use. At each revolution of the crank-shaft yielding pressure is thus applied to the hinged box side 16^b by the finger 18, result-

ing in gradually checking the shuttle as the latter enters the box and continued revolution of the crank-shaft operates to move the said finger outward thus removing all 5 clamping and restraining influence from the shuttle.

Having thus described my invention I claim:—

1. In a device of the character described, 10 the combination with the swords of a loom, of a batten supported upon said swords, a shuttle box carried by said batten and comprising a movable side wall, an actuating member for said movable wall pivoted upon 15 said batten, a lever pivoted upon one of said swords, a yieldable connection between said lever and said actuating member, a driving member and independent connections between said driving member and the batten 20 and said driving member and said lever for imparting bodily movement to the batten

and movement to the said movable wall in timed relation to the movement of the batten, said independent connection for imparting movement to said wall comprising an adjustable angle plate and a link. 25

2. In a device of the character described, the combination with the swords of a loom, of a batten supported upon said swords, a shuttle box carried by said batten and comprising a movable side wall, an actuating member for said movable wall pivoted upon 30 said batten, a lever pivoted upon one of said swords, a rod pivotally connected to the actuating member and passing through said lever, a collar carried by said rod and a spring bearing between said collar and said lever. 35

NOE LARIVIERE.
